UNITED STATES PATENT OFFICE.

FRANKLIN E. POINDEXTER, OF DENTON, TEXAS, ASSIGNOR, BY MESNE ASSIGNMENTS,
TO BENJAMIN S. DAVIDSON, OF DENTON, TEXAS.

SHOCK ABSORBER.

Application filed February 24, 1920, Serial No. 360,666. Renewed September 25, 1922. Serial No. 590,540.

To all whom it may concern:

Be it known that FRANKLIN E. POINDEXTER, a citizen of the United States, residing at Denton, in the county of Denton and 5 State of Texas, has invented certain new and useful Improvements in Shock Absorbers, of which the following is a specification.

In the drawing:

The improved fluid pressure device comprises a cylindrical casing 1, the upper end 10 of which is closed by a cap 2, threaded to said cylinder against gasket 3. The cap is provided with plug 4, for the introduction of oil or other liquid and an inwardly opening valve 5 which serves as a means of introducing additional fluid, or the escape of same under certain conditions as will be explained.

The plunger 6, is attached to cap 2, by 20 suitable means as threading into same and extends into cylinder 7, which is attached to and carried by a main piston 8, slidably mounted in casing 1. The said plunger is provided with an upwardly opening valve 9, and a port 10, which permits oil and fluid to pass from compartment 11, to compartment 12.

The main piston is provided with a ring shaped diaphragm 13, extending from the 30 piston wall to cylinder 9, and separating the main piston compartment 14, from compartment 12. The diaphragm is provided with a plug 15, which is provided with a constricted passage, and extends above diaphragm 13.

Cylinder 7, is provided with a port 17, which connects compartments 11, and 14.

The upwardly opening valve 18, is seated 40 against a seat 19, preferably of copper and is secured by means of expansion with a tool which throws the outer edge of seat against its retaining wall.

The main piston 8, is provided with a partition 20, having formed integral with it 45 chamber wall 21, which receives cylinder 7, chamber wall 22, and 23, which extends to lower part of compartment 24, formed by the main piston wall and the cup 25, the said cup being held in place by a screw or 50 screws 26.

The main piston wall is provided with suitable packing rings 27, and oil scraping ring 28, a dirt scraping ring 29, oil port 30, and a longitudinal slot or groove 31, so shaped to pass over the end of screw 32, 55 which limits the downward motion of the main piston 8.

Cup 25, is provided with a port 33, leading to groove 31, in conjunction with which it forms an air inlet to compartment 24, and 60 a means 33^a, of connecting the main piston to one of the vibrating members as the spring 34, of an automobile.

A means of connecting the casing 1, to the other vibrating member as the frame of the 65 vehicle is shown at 35.

A means at 36, of connecting a bumper to extend to a similar device on the opposite side of the vehicle.

Valve 5, is held normally in a closed position by spring 37. Spring 36, is secured to valve 5, and in conjunction with the flexible connection 38, which is secured to diaphragm 13, forms a valve opening means the use of 70 which will be described.

The pin 40, limits the movement of ball valve 9.

The port 41, serves to control the pumping action as will be explained in the operation of the device. 80

Spring 42, serves to support the load when the internal pressure is not sufficient to do so.

Cup 25, is provided with a small wick hole 44, by means of which the shackle bearing that attaches to spring of vehicle is 85 lubricated.

The operation of the device is as follows:

Suppose that the internal pressure of the device is atmospheric and that it is attached 90 to the vibrating parts of a vehicle as shown, the inward thrust of the main piston being resisted by the compression of spring 42.

When the vehicle is put in motion, the pressure exerted on the main piston by 95 spring 34, of the vehicle will vary from time to time and the piston will move in and out of shell 1, under the influence of spring 42. This movement of the main piston and cylinder 7, which it carries brings about 100

changes in the volume of compartment 11. The consequent pressure changes in said compartment forces oil and air through valve 9, and port 10, into the main pressure chamber 12. When the volume of compartment 11 is suddenly increased, the pressure is decreased. Oil is forced into said compartment through the constricted port 17, and air is forced in under atmospheric pressure through port 33, tube 23, and valve 18. The pressure change for a given volume change in compartment 11, is inversely proportional to the air space above the oil in said compartment. The constricted port 17, insures a supply of oil in compartment 11, as long as there is any oil in the lower part of the main piston chamber 14, which serves as an oil reservoir.

The compartment 12 constitutes and will be hereinafter referred to as the main pressure chamber, while the compartment 14 constitutes and will be hereinafter referred to as the oil reservoir. The compartment 11 is in reality a pump chamber, and it is to be particularly noted that the pump chamber 11 and the oil reservoir are in communication thru the restricted opening 17. This opening is important in the operation of the device, and to emphasize the importance of this feature it will be assumed that the main piston 8 is for any reason caused to move downward. This of course removes the cylinder 7 defining the pump chamber downwardly and increases the area of such chamber below the plunger 6. Owing to the restricted opening 17 however, oil from the reservoir 14 cannot enter the pump chamber 11 with sufficient rapidity to fill the additional space thus provided, which of course is in the nature of a partial vacuum, and hence such space will be filled with air from the atmosphere entering thru passage 31, port 33 and past valve 19. Thus in what may be termed a separating movement of the respective elements 1 and 8 of the shock absorber, a quantity of air from the atmosphere enters the space beneath the pump plunger 6. In the movement of the members 1 and 8 in the opposite direction, that is, toward each other, the main pressure chamber is reduced in size, materially increasing the pressure in such chamber, and at the same time the pump plunger 6 moves into the pump chamber a corresponding distance. As the area of the pump chamber is materially less than that of the main pressure chamber, the air trapped in the pump chamber as previously described is increased in pressure proportionally greater than the increase in the main pressure chamber. Hence this air in the pump chamber 11 will be forced by the valve 9 and into the main pressure chamber. Were it not for the restricted opening 17 and the resultant limited flow of oil from the reservoir to the pump chamber, it is apparent that little or any air from the atmosphere would be permitted to enter the pump chamber for the pumping operation, and hence the device would be ineffective for increasing the pressure of the main pressure chamber in accordance with the load.

The oil which is forced through valve 9, returns through ports 10, and 16, to compartment 14, the depth of the layer of the oil seal on diaphragm 13, being determined by the length of tube 15.

The air which is taken in in this pumping process increases the internal pressure, the main piston being forced down releasing the pressure on spring 42. This pumping process will continue until the end of the plunger 6, takes a position above port 41, at which point the intaking of air from the outside is discontinued the air in compartment 11, being forced back and forth through said port, there being only slight pressure changes in said compartment.

Valve 5, serves two purposes. First, it can be used to introduce air into the device and spring 42, could thus be dispensed with, the air cushion allowing the main piston and shell 1, to move relative to each other under the vibratory influence of the vehicle. Spring 42, could also be placed between the vibrating members at some point without the shell, as indicated at 43. All that is necessary for the pumping process to be established is that the main piston and shell 1, shall move relative to each other under the influence of the vibrations incident to motion of the vehicle.

The other function of valve 5, in conjunction with the flexible connection 38, and spring 36, is to relieve any excess pressure incident to removing the load on the vehicle. The volume to which the device will pump is determined by the position of port 41, and the length of plunger 6. In case the load on the vehicle is removed, the main piston would move down until the internal pressure is decreased a corresponding amount. In cases where the load change is great, as in trucks, the excessive downward movement would be objectionable. The length of the flexible connection 38, limits this downward movement of the main piston by opening valve 5, against the compression of spring 37. Spring 36, is to prevent the breaking of connection 38.

Thus the volume under all load conditions is determined by the position of port 41, the length of plunger 6, and the length of connection 38.

Port 16, serves as an oil and air passage between compartments 12, and 14. It is made small so that the gradual equalization of the pressure between said compartments will slow up motion of main piston gradually.

The layer 44, of loose material, as felt, is for the purpose of removing grit or dirt which might work past the dirt scraping ring 29, and be washed into cup 25, with the oil that the oil scraping ring 28, scrapes from the interior of casing 1.

Having thus described the invention, what is claimed as new is:

1. A fluid pressure device, comprising a casing, a main piston movable therein and formed to provide an oil reservoir to contain a constant supply of oil, a pump cylinder carried by the main piston and providing a pump chamber, a hollow plunger connected to the casing and operating in the cylinder, an air inlet to the pump chamber, and a restricted opening forming a constant communication between the oil reservoir and pump cylinder under all working conditions, whereby to retard the flow of oil between the reservoir and pump chamber with respect to any pump action.

2. A fluid pressure device comprising two main elements slidably connected and adapted to define a main pressure chamber between them, one of said elements being formed to provide an oil reservoir and a pump chamber in communication with the reservoir thru a restricted opening, the other of said elements having a plunger operating in the pump chamber whereby the flow of oil to and from the pump chamber relative to the reservoir is limited by the restricted opening, the tendency to vacuum formation by the movement of the plunger and the corresponding restricted flow of oil being compensated for by air admitted from the atmosphere.

3. A fluid pressure device comprising a casing, a piston operative therein, and defining a main pressure chamber therebetween, a pump including a pump cylinder connected to one of said elements and a plunger connected to the other of said elements, an air inlet to the pump cylinder below the plunger, and means for permitting a liquid to flow to and from a pump cylinder under action of the plunger, the said means preventing a sufficient flow of liquid to said cylinder in a rapid movement of the plunger to compensate for the plunger movement, whereby air is drawn thru said inlet to compensate for the space not occupied by the oil.

4. A fluid pressure device comprising a main pressure chamber, a pump for supplying pressure to said chamber and including a pump cylinder and a plunger operative therein, the pump cylinder having an air inlet, and means wholly independent of the air inlet to admit a liquid to the pump cylinder under a suction action of the plunger, said means being so restricted as to prevent a liquid admission to fully compensate for the plunger movement, whereby air will enter

the pump cylinder thru the air inlet under the vacuum created by the plunger in its movement in excess of the fluid supply.

5. A fluid pressure device comprising slidably cooperative members defining a pressure chamber, a pump operated in the movement of the members for supplying pressure to said chamber, an oil reservoir having a restricted communication under all working conditions with the pump, the suction action of the pump being partially compensated for by the limited admission of a liquid to the pump, the pump having an air inlet to admit air under the suction stroke of the pump to the extent defined by the suction of the pump in excess of the liquid admission under such suction.

6. A fluid pressure device comprising a casing, a piston movable therein and forming a pressure chamber between one end thereof and the casing, a pump cylinder arranged within the piston, a pump plunger connected to and operated by the casing, an oil reservoir formed by the interior of the piston and a restricted communication open under all working conditions between said reservoir and pump cylinder below the plunger, said pump cylinder having an air inlet.

7. A fluid pressure device comprising a casing, a piston movable therein and forming a pressure chamber between one end thereof and the casing, a pump cylinder arranged within the piston, a pump plunger connected to and operated by the casing, an oil reservoir formed by the interior of the piston and a restricted communication between said reservoir and pump cylinder below the plunger, said pump cylinder having an air inlet, and a relief valve for the pressure chamber operated in the relative movement of the piston.

8. A fluid pressure device, comprising a casing, a main piston movable therein formed to provide an oil reservoir to contain a constant supply of oil, a pump operable in the relative movement of the piston and casing, an air inlet open to the suction action of the pump, and a communication between the pump and oil reservoir open under all working conditions and so restricted that a pump action can neither draw oil from the reservoir nor force oil to the reservoir in complete correspondence with the pump action.

9. A fluid pressure device, comprising a casing, a main piston movable in the casing and formed to provide an oil reservoir containing a constant supply of oil, a pump including a pump chamber operated in the relative movement of the casing and piston and drawing upon said reservoir in suction stroke and forcing material from the pump chamber to the reservoir in pressure stroke, there being an open connection between said

41
pump and reservoir under all working conditions of the device, which connection is so restricted as to retard the flow of oil between the reservoir and pump chamber in either direction as compared with any pump action, whereby in a suction stroke the supply of liquid to the pump chamber is less than the capacity of the space provided, and in the

pressure stroke of the pump, the flow of oil from the pump chamber is less than the reduced space demands, whereby in the latter instance, a supply of oil is directed from the pump chamber away from said reservoir. 10

In testimony whereof I affix my signature.

FRANKLIN E. POINDEXTER.
